REFRIGERATION

Erik August Forsberg, Stockholm, Sweden, assignor, by mesne assignments, to Servel, Inc., New York, N. Y., a corporation of Delaware

Application December 31, 1935, Serial No. 56,879
In Sweden August 25, 1933

15 Claims. (Cl. 62—5)

This invention relates to refrigeration and more particularly to control of continuous refrigeration produced with the aid of a plurality of refrigeration systems of an intermittent type, and 5 it is an object of the invention to provide an improved arrangement by means of which a more exact control of heat input responsive to the refrigerating requirements and distribution of work between a plurality of systems is effected 10 in a simple and dependable manner.

The invention, together with the objects and advantages thereof, will become apparent upon consideration of the following description taken in connection with the accompanying drawings 15 in which:

Fig. 1 shows diagrammatically a refrigerator embodying the invention; and

Fig. 2 illustrates a modification thereof.

Referring to Fig. 1, there are shown two absorption systems of an intermittent type. The first system, herein referred to as system A, comprises a generator-absorber 10, a condenser 11, a receiver 12, and an evaporator 13. The generator-absorber 10 is provided with a suitable heating element as, for instance, an electric heating resistance element 14. The generator-absorber 10 is provided with heat radiation fins 15 for air cooling, and is located and vertically movable within a thermally insulated jacket or flue 16 which is open at the bottom. The generator-absorber 10 is connected to the condenser 11 by means of a conduit 17 including a flexible portion 18 which permits vertical movement of the generator-absorber within the jacket or flue 16. The condenser 11 is provided with heat radiation fins 19 for air cooling. The evaporator 13 is in the form of a coil provided with heat transfer fins, and is located in the upper part of a thermally insulated refrigerator storage compartment 20. Both ends of the evaporator coil 13 are connected to the receiver 12 which is embedded in the thermal insulation around the refrigerator compartment 20. The receiver 12 is connected by means of a conduit 21 to the condenser 11.

It will be understood that the refrigeration system just described is merely illustrative of this type of system and is shown only diagrammatically for the purpose of explaining the present invention which is not thus limited. The refrigeration system contains a suitable absorbent such as water in the generator-absorber 10, and a refrigerant fluid such as ammonia which is soluble in the absorbent. In operation, heat is applied to the generator-absorber 10 by connecting the heating element 14 to a source of electricity 22, as

hereinafter described. Ammonia vapor is expelled from solution by heating in the generator-absorber, the vapor flowing through the flexible conduit 18 and conduit 17 to the condenser 11. The ammonia vapor is condensed to liquid in the condenser, and the liquid flows through conduit 21 into the receiver 12 and evaporator coil 13. This process takes place during what is referred to as a generating or heating period. Heating of the generator-absorber 10 is 10 then discontinued, and the latter is cooled by upward flow of air through the jacket or flue 16. Upon decrease in temperature of the generator-absorber 10, the pressure in the system decreases due to absorption of refrigerant vapor into solution in the weakened liquid in the generator-absorber, and, when the pressure is sufficiently reduced, liquid refrigerant evaporates in the evaporator coil 13, whereby refrigeration is produced. This process continues during a period which 15 may be referred to as a refrigerating or absorbing period. A generating period and an absorbing period constitute a cycle of operation of the system.

The second refrigeration system, herein referred to as system B, is like the previously described system A and comprises a generator-absorber 30, a condenser 31, a receiver 32, and an evaporator coil 33. The evaporator coil 33 is also located in the refrigerator compartment 20. The generator-absorber 30 is provided with an electric heating element 34 and heat radiation fins 35, and is also vertically movable within a thermally insulated jacket or flue 36. The generator-absorber 30 is connected to the condenser 31 by means of a conduit 37 having a flexible portion 38 which permits vertical movement of the generator-absorber within the jacket or flue 36. The condenser 31 is provided with heat radiation fins 39 for air cooling. The evaporator coil 33 is connected to 20 the receiver 32 which is embedded in the thermal insulation around the refrigerator compartment 20, and the receiver is connected by means of a conduit 41 to the condenser 31.

It will now be understood that continuous refrigeration of the storage compartment 20 may be had by alternating the absorption or refrigerating periods of the two systems A and B, that is, operating the systems so that the generating period of system A occurs during the absorption 25 or refrigerating period of system B, and so that the absorption or refrigerating period of system A may be started at the termination of the refrigerating period of system B. It is desirable that heat input to system A be terminated at 30

the end of a generating period whether or not system B has reached the end of its refrigerating period. It is also desirable that cooling of the generator-absorber 10 of system A be started sufficiently ahead of the termination of the refrigerating period of system B so that the pressure in system A will be sufficiently reduced to instigate refrigeration immediately upon termination of the refrigerating period of system B. 5

10 It is further desirable that control of systems A and B be effected during their respective refrigerating periods so that a desired temperature may be automatically maintained in a refrigerator storage compartment 20. This is all accomplished by the control now to be described. 15

The generator-absorber 10 is mounted on one end of a lever 42 which is suitably pivoted at 43 and the movement of which is limited by suitable stops 44. The weight of the generator-absorber 20 10 is counterbalanced by weight 45 on the other end of lever 42. A weight or inverted pendulum 46 is arranged on lever 42 so that it moves back and forth across dead-center of the lever system as the generator-absorber 10 moves up and down 25 in the flue 16. When the generator-absorber 10 is in its lower position, as illustrated in Fig. 1, the effect of weight 46 is added to the weight of the generator-absorber and liquid contained therein. As refrigerant vapor is expelled from 30 solution in the generator-absorber 10, the latter becomes lighter and rises until the weight 46 moves over dead-center and is added to the counterbalancing weight 45, whereupon the lever 42 moves quickly due to the sudden unbalance, and the generator-absorber 10 is carried to its upper position. 35

The second generator-absorber 30 of system B is likewise mounted on a lever 52 pivoted at 53 and provided with stops 54. The generator-absorber 30 is counterbalanced by a weight 55, and the lever 52 is provided with a weight or pendulum 56 which moves back and forth across dead-center as explained in connection with system A in the preceding paragraph. 40

45 The electric heating element 14 in system A is connected by a wire 60 to one side of the source of electrical current 22. The circuit of the heating element 14 is adapted to be completed by means of a wire 61, electrical contacts 62, wire 63, electrical contacts 64, and a wire 65.

50 The heating element 34 of system B is connected to one side of the source of electrical current 22 by means of a wire 70. The circuit of the heating element 34 is adapted to be completed by means of a wire 71, electrical contacts 72, a wire 73, electrical contacts 74, and a wire 75.

55 The electrical contacts 62 and 74 are part of a switch operated by the lever 42 of system A, and contacts 64 and 72 are part of a switch operated by the lever 52 of system B. Thus, the circuit to the heating element 14 is completed only when the generator-absorber 10 is down and the generator-absorber 30 is up, as illustrated in Fig. 1. Assume now that the end of the generating period for system A is reached. The lightened generator-absorber 10 rises due to the overbalance of weight 46, and lever 42 operates to open contacts 62 and close contacts 74. 60

70 Heating of the generator-absorber 10 is thus discontinued. However, the operation of system B is not affected. When the generator-absorber 30 of system B becomes sufficiently weight'd, at the end of the refrigerating or absorption period 75 of this system, the lever 52 is operated to open

contacts 64 and close contacts 72. Thereupon, the circuit of the heating element 34 is completed and the generating period of system B is instigated.

5 As previously indicated, the generator-absorber 10 of system A is cooled by upward flow of air through the insulated flue 16. An upper continuation 16 of the flue 16 is provided with dampers 78 and 80. Likewise, an upper continuation 19 of the flue 36 for system B is provided with dampers 80 and 81. The dampers 78 and 80 are operated together to regulate the temperature of refrigeration. As shown in Fig. 1, the dampers 78 and 80 are interlocked by means of a rod 82 which is operatively connected 15 by means of a lever 83 to an operating member 84 of a thermostat. The sensitive bulb 85 of the thermostat is located in the refrigerator storage compartment 20 so that the dampers 78 and 80 are operated responsive to temperature in the 20 refrigerator compartment. The dampers 78 and 80 are closed upon decrease in temperature, and opened upon increase in temperature. Thus, flow of air over the generator-absorbers 10 and 30 is controlled so that whichever is operating to 25 produce refrigeration is cooled to the extent necessary to maintain a desired temperature in the storage compartment 20.

30 The damper 77 in system A is operated by the lever 42, being operatively connected thereto by 30 means of a rod 86, a bell-crank 87, and a rod 88. It will be understood that the operative connection to the damper 77 is such that this damper is closed during the heating or generating period and is opened upon termination of the 35 heating period and remains open until the beginning of the next heating period. The damper 81 in system B is operatively connected by means of a rod 89, a bell-crank 90, and a rod 91 to the lever 52. The damper 81 is thus open 40 except during the heating period of system B. It will now be understood that dampers 77 and 81 cut off flow of air over the generator-absorbers 10 and 30 only during the respective heating periods of systems A and B, and at other times 45 leave control of the air flow to the dampers 78 and 80 responsive to temperature in the refrigerator compartment 20.

50 With the control just described in connection with Fig. 1, the damper 77 is opened and cooling 50 of the generator-absorber 10 starts immediately upon termination of the heating period of system A, whether or not system B has yet reached the end of its absorption or refrigerating period. Under certain conditions, therefore, it could occur 55 that the generator-absorber 10 would be sufficiently cooled so that system A would start to produce refrigeration before termination of the refrigerating period of system B. In order to delay cooling of the generator-absorbers until 60 termination of the respective refrigerating periods of the other system, the dampers 77 and 81 may be controlled as illustrated in Fig. 2. In this figure, like parts are indicated by the same reference numerals as in Fig. 1. The dampers 77 and 81 are interlocked by means of a rod 92 having projecting members 93 and 94. The rod 92 is connected between the lever 42 and a bell-crank 95. The rod 91 is connected between the lever 52 and a bell-crank 96. The bell-cranks 65 95 and 96 are operatively associated respectively with the projections 94 and 93 in a manner to each move the rod 92 in one direction only. The bell-crank 95 operates to move the rod 92 to close 70 damper 77 and open damper 81. The bell-crank 75

96 operates the rod 92 to close damper 81 and open damper 71. It will now be understood that, at the end of the heating period of system A, the dampers 71 and 81 will not be operated, and 5 cooling of the generator-absorber 10 will not begin except as it may cool slowly by radiation which is retarded by the insulated jacket or flue 16. However, when system B reaches the end of its absorption or refrigerating period, damper 81 10 will become closed and damper 71 opened, thereby placing the cooling of the generator-absorber 10 under the control of the thermostatically operated damper 78.

It will be understood that various modifications 15 and changes may be made within the scope of the invention which is not limited to that which is shown in the drawings and described in the specification but only as indicated in the following claims.

20 What is claimed is:

1. A refrigerator including a plurality of intermittent absorption refrigeration systems having alternate heating and refrigerating periods, a heater for each of said systems, and means for 25 automatically controlling operation of said systems including shutting off a heater at the end of a heating period of the respective system without affecting operation of another of said systems.

2. A refrigerator including a plurality of intermittent absorption refrigeration systems having alternate heating and refrigerating periods, a heater for each of said systems, and means for 30 automatically controlling operation of said system including shutting off a heater of a respective system prior to termination of a refrigerating period of another of said systems so that cooling of said first system may occur and said first system be ready to produce refrigeration upon termination of a refrigerating period of said 35 second system.

40 3. A refrigerator including a plurality of intermittent absorption refrigeration systems having alternate heating and refrigerating periods, a heater for each of said systems, means for automatically controlling operation of said systems 45 including shutting off a heater at the end of a heating period of the respective system without affecting operation of another of said systems, and means for delaying cooling of said first system so that it will not start to produce refrigeration until termination of a refrigerating period of said second system.

45 4. In a process of continuous refrigeration with the aid of a plurality of intermittent absorption refrigeration systems having alternate heating and refrigerating periods, that improvement 50 which consists in terminating a heating period of one of said systems responsive to a condition in said system without affecting operation of another of said systems.

55 5. In a process of continuous refrigeration with the aid of a plurality of intermittent absorption refrigeration systems having alternate heating and refrigerating periods, that improvement 60 which consists in terminating a heating period of one of said systems responsive to a condition of said system occurring prior to termination of a refrigerating period of another of said systems whereby cooling of said first system may commence and said first system be ready to produce refrigeration upon termination of the refrigerating period of said second system.

65 6. In a process of continuous refrigeration with the aid of a plurality of intermittent absorption refrigeration systems having alternate heating 70 and refrigerating periods, that improvement which consists in terminating a heating period of one of said systems responsive to a condition of said system occurring prior to termination of a refrigerating period of another of said systems whereby cooling of said first system may commence and said first system be ready to produce refrigeration upon termination of the refrigerating period of said second system.

75 7. A refrigerator including a plurality of intermittent absorption refrigeration systems having alternate heating and refrigerating periods, each system including a generator-absorber, means for heating said generator-absorber, means for cooling said generator-absorber, and means for alternately operating said heating and cooling means constructed and arranged so that said heating means is shut off without affecting operation of another of said systems.

80 and refrigerating periods, that improvement which consists in terminating a heating period of one of said systems responsive to a condition of said system occurring prior to termination of a refrigerating period of another of said systems 5 and retarding cooling of said first system so that it will not produce refrigeration until termination of a refrigerating period of said second system.

85 8. A refrigerator including a plurality of intermittent absorption refrigeration systems having alternate heating and refrigerating periods, each system including a generator-absorber, means for heating said generator-absorber, means for cooling said generator-absorber, and means for alternately operating said heating and cooling means constructed and arranged so that said heating means is shut off without affecting operation of another of said systems.

90 9. A refrigerator including a plurality of intermittent absorption refrigeration systems having alternate heating and refrigerating periods, each system including a generator-absorber, means for heating said generator-absorber, means for cooling said generator-absorber, and means for alternately operating said heating and cooling means constructed and arranged so that said heating means is shut off without affecting operation of another of said systems, and means for regulating operation of said cooling means to maintain a desired temperature in the refrigerator.

95 10. A refrigerator including two intermittent absorption refrigeration systems each including a generator-absorber, means for heating said generator-absorber, and means for cooling said generator-absorber, and means for alternately operating the heating and cooling means of each of said systems constructed and arranged so that the heating means of one of said systems is shut off without affecting operation of the other system and cooling of said first system is retarded until termination of a refrigerating period of said second system.

100 11. A refrigerator including two intermittent absorption refrigeration systems each including a generator-absorber, means for heating said generator-absorber, and means for cooling said generator-absorber, and means for alternately operating the heating and cooling means of each of said systems constructed and arranged so that the heating means of one of said systems is shut off without affecting operation of the other system and cooling of said first system is retarded until termination of a refrigerating period of said second system, and means for regulating operation of said cooling means to maintain a desired temperature in the refrigerator.

105 12. In a refrigerator having a compartment to be cooled, two intermittent absorption refrigeration systems each including a cooling element in said refrigerator compartment, a condenser, a generator-absorber, a heater for said generator-absorber, a conduit for conducting fluid for cooling said generator-absorber, a first valve for controlling flow of fluid in said conduit, and a second valve for opening and closing said conduit, a thermostat for regulating said first valve of both systems to maintain a desired temperature in said compartment, a supply line for each heater including two 110 control devices in series, and means associated with each system operative at the end of each period in the cycle of operation of the respective system to operate one of said two control devices in the heater supply line of the respective system and 115

operate one of the two control devices in the heater supply line of the other system and close said second valve of the respective system at the end of the absorption period.

- 5 12. In a refrigerator having a compartment to be cooled, two intermittent absorption refrigeration systems each including a cooling element in said refrigerator compartment, a condenser, a generator-absorber, an electric heating element for said generator-absorber, a conduit for conducting fluid for cooling said generator-absorber, a first valve for controlling flow of fluid in said conduit, and a second valve for opening and closing said conduit, a thermostat for regulating 10 said first valve of both systems to maintain a desired temperature in said compartment, an energizing circuit for each heating element including two switches in series, and a control device associated with each system, said control device being operative at the end of each heating period 15 in the cycle of operation of the respective system to open one of said two switches in the heating circuit of the respective system and close one of the two switches in the heating circuit of the other system, and said control device being operative at the end of each absorption or refrigerating period in the cycle of operation of the respective system to close said switch in the heating circuit of the respective system and open said 20 switch in the heating circuit of the other system and close said second valve of the respective system.

13. In a refrigerator having a compartment to be cooled, two intermittent absorption refrigeration systems each including a cooling element 30 in said refrigerator compartment, a condenser, a generator-absorber, a heater for said generator-absorber, means for cooling said generator-absorber, a first device for regulating said cooling means, and a second device for stopping operation of said cooling means, a thermostat for operating said first device of both systems to maintain a desired temperature in said compartment, and a control device associated with each system, said control device being operative at the 35 end of each heating period in the cycle of operation of the respective system to shut down said heater of the respective system and to start the heater at the end of each absorption or refrigerating period, and means to operate said second device to stop operation of said cooling means at the end of each absorption period of the respective system.

14. In a refrigerator having a compartment to be cooled, two intermittent absorption refrigeration systems each including a cooling element in 50 said refrigerator compartment, a condenser, a generator-absorber, an electric heating element

for said generator-absorber, a conduit for conducting fluid for cooling said generator-absorber, a first valve for controlling flow of fluid in said conduit, and a second valve for opening and closing said conduit, a thermostat for regulating said first valve of both systems to maintain a desired temperature in said compartment, an energizing circuit for each heating element including two switches in series, and a control device associated with each system, said control device being operative at the end of each heating period 5 in the cycle of operation of the respective system to open one of said two switches in the heating circuit of the respective system and close one of the two switches in the heating circuit of the other system, and said control device being operative at the end of each absorption or refrigerating period in the cycle of operation of the respective system to close said switch in the heating circuit of the respective system and open said 10 switch in the heating circuit of the other system and close said second valve of the respective system.

15. In a refrigerator having a compartment to be cooled, two intermittent absorption refrigeration systems each including a cooling element in said refrigerator compartment, a condenser, a generator-absorber, an electric heating element for said generator-absorber, a flue for conducting air in cooling relation to said generator-absorber, 30 a first damper for controlling flow of air in said flue, and a second damper for opening and closing said flue, a thermostat for regulating said first damper of both systems to maintain a desired temperature in said compartment, an energizing 35 circuit for each heating element including two switches in series, and a control device associated with each system, said control device being operative at the end of each heating period in the cycle of operation of the respective system to open 40 one of said two switches in the heating circuit of the respective system and close one of the two switches in the heating circuit of the other system, and said control device being operative at the end of each absorption or refrigerating period 45 in the cycle of operation of the respective system to close said switch in the heating circuit of the respective system and open said switch in the heating circuit of the other system and close said second damper of the respective system. 50

ERIK AUGUST FORSBERG.
